UNITED STATES PATENT OFFICE

160,079

COMBINED TRAY AND BOBBY PIN OPENER

William F. Feyrer, Englewood, N. J., assignor to Solo Products Corporation, a corporation of
New Jersey

Application August 30, 1949, Serial No. 4,766

Term of patent 14 years

(Cl. D86—10)

To all whom it may concern:

Be it known that William F. Feyrer, a citizen of the United States, residing at 10 Cedar Lane, Englewood, county of Bergen, and State of New Jersey, has invented a new, original, and ornamental design for a Combined Tray and Bobby Pin Opener, of which the following is a specification, reference being had to the accompanying drawing forming part thereof:

The single figure of the drawing is a perspective view of a combined tray and bobby pin opener showing my new design.

I claim:

The ornamental design for a combined tray and bobby pin opener, substantially as shown.

WILLIAM F. FEYRER.
